DESIGN FOR A DRESS

Eugenia Staber, New York, N. Y.

Application May 18, 1939, Serial No. 85,073

Term of patent 7 years

To all whom it may concern:

Be it known that I, Eugenia Staber, a citizen of the United States of America, resident of New York city, county of New York, and State of New York, have invented a new, original, and ornamental Design for a Dress, of which the following is a specification, reference being had to the accompanying drawing forming a part thereof, in which,

I claim:

The ornamental design for a dress, substantially as shown.

EUGENIA STABER.
